UNITED STATES PATENT OFFICE.

JOHN OWENS, OF WASHINGTON, DISTRICT OF COLUMBIA.

GREASE CUP.

Application filed September 16, 1921. Serial No. 501,160.

To all whom it may concern:

Be it known that I, JOHN OWENS, a citizen of the United States, residing at Washington, in the District of Columbia, have invented certain new and useful Improvements in Grease Cups, of which the following is a specification.

This invention relates to grease cups and more particularly to those grease cups that are attached to the bearing parts of automobiles or other vehicles using grease in a semi-fluid condition.

One of the objects of the present invention is to furnish a grease cup that will remain tightly closed after the grease is inserted therein and yet which can be easily opened for the insertion of additional supplies of grease, and furthermore will exclude dirt or dust from the mouth of the cup.

Another object of the invention is to so attach the parts of the cup and nozzle that they cannot readily be detached or become lost.

Another object of the invention is to so arrange the parts of the cup and cover that the cover may be readily removed and a nozzle properly constructed may be readily attached to the cup after the cover has been removed, the nozzle being so constructed that when grease is forced from a grease gun or similar apparatus into the cup, it will not be allowed to escape around the fittings of the parts.

With the foregoing objects outlined and other objects in view which will appear as the description proceeds, the invention consists in the novel features hereinafter described in detail, illustrated in the accompanying drawing and more particularly pointed out in the appended claims.

Referring to the drawing:

Figure 1 is a sectional view of the grease cup attached to the parts to be lubricated with the top attached to the cup;

Fig. 2 is a sectional view of the cup removed and the nozzle attached to the cup.

In the drawing 1 designates the cup which in the embodiment shown has projecting therefrom pins 2 to co-act with a suitable bayonet slot in the top 3 of the cup. The top or cover for the cup may be cylindrical in form to snugly fit the outside of the cup and has therein a piston-like stopper 4 with a projection 5 extending therefrom having an enlarged head 6. The projection 5 ex-

tends through a hole 7 in the top of the cover and a spring 8 around the projection 5 and between the piston-like part 4 and the top of the cup holds the piston-like part 60 in contact with the top of the cup.

The piston-like part 4 should of course have seating surfaces 9 to fit corresponding surfaces on the end of the cup. It is within the scope of this invention to have these 65 surfaces either conical in shape, or flat, or otherwise just so one surface fits upon the other to prevent the egress of grease and the ingress of dust and dirt.

The cup may have a ball valve 10 fitting 70 in a corresponding opening in a nut 11 screwed or otherwise fastened in the top of the cup, the nut 11 forming the valve seat and being easily removed to take out the valve 10 or for repairs, cleansing, etc. 75

The valve 10 may be held to its seat by a spring 12 which may be conveniently seated on a ledge 13 in the cup.

The valve 10 may have extending therefrom a projection 14 comprising a neck part 80 and a head suitably shaped for the attachment thereto of the end of the spring 12. The construction shown has been found to be efficient for holding the valve to its seat but evidently various other devices might be 85 substituted therefor.

When it is desired that grease be inserted into the cup the top may be quickly removed by unfastening the bayonet slot joint and attaching to the cup the nozzle shown in 90 Fig. 2. This nozzle comprises a cylindrical part 15 of a size and having therein a bayonet slot similar to that of the cup cover 3. The cylindrical part may have a threaded top into which may be threaded a nut 16, the 95 nozzle 17 having thereon a shoulder 18 against which the end of the nut 16 rests. The end of the nozzle 19 is made to closely fit the interior of the cylindrical part 15 and also the end of the cup 1. 100

It is evident from the construction shown that the cup cover 3 may be easily removed from the cup and the nozzle having the cylindrical part 15 attached instead of the cover, then by giving the nut 16 a turn or two the end of the nozzle may be brought and held into close contact with the end of the cup so that when pressure is put upon the grease in the grease gun to force the same through the nozzle into the cup, the 110 grease cannot escape by oozing through the closely fitting parts.

It may also be readily seen that the cylindrical part of the cover cannot become detached from the cover and be lost, nor can the parts of the nozzle be easily detached and become lost, while at the same time they are adapted to be quickly detached and attached when grease is to be forced into the bearings. Even if the nut 16 should become entirely unscrewed from the cylindrical portion 15 it cannot be lost since the parts would be still held together, nor will the valve 10 be easily displaced or lost.

From the foregoing, I believe that the construction, operation and advantages of my improved cup and nozzle will be readily understood by those skilled in the art and I am aware that various changes may be made in the construction illustrated without departing from the spirit of the invention as expressed in the following claims.

I claim as my invention:—

1. A grease cup having a cover with an opening therein, a part fitting over the outside of the end of the cup and having a part extending through said opening, and means for preventing separation of the cover and said part.

2. A grease cup having a cover with an opening therein, a part fitting over the out-

side of the end of the cup and extending through said opening, means for preventing separation of the cover and said part, and a valve seat in the end of the cup and a valve cooperating with said seat.

3. A grease cup, a detachable cover therefor having an opening in its end, a part extending over the outside of the end of the cup and up through said opening, and means between the cover top and said part for holding said part in close contact with the cup.

4. A grease cup, a detachable cover therefor having an opening in its end, a part extending through said opening, means between the cover top and said part for holding said part in close contact with the cup, and a detachable valve seat and valve in the cup.

5. The combination of a cup, a part fitting over the top of the cup, a detachable cover for the cup, said cover being screw threaded at one end, a nut for the screw threaded end, and a shoulder on said part against which the screw nut operates to hold the end of said part in close contact with the end of the cup.

In testimony whereof I hereunto affix my signature.

JOHN OWENS.
